CLAIM

The ornamental design for a three-wheeled motorcycle, as shown.

DESCRIPTION

FIG. 1 is a top plan view of a three-wheeled motorcycle showing our new design;

FIG. 2 is a front perspective view thereof;

FIG. 3 is a side elevation view of the right side thereof;

FIG. 4 is a side elevation view of the left side thereof;

FIG. 5 is a back perspective view thereof;

FIG. 6 is an oblique perspective view principally illustrating the left side thereof.

FIG. 1.

FIG. 2.

FIG. 3.

FIG. 5.

FIG. 4.

FIG. 6.
